UNITED STATES PATENT OFFICE.

HUGH G. HILL, OF WHEELING, WEST VIRGINIA, ASSIGNOR, BY MESNE ASSIGNMENTS,
TO WHITAKER-GLESSNER COMPANY, OF WHEELING, WEST VIRGINIA.

CAN-SEAMING MACHINE.

1,398,018.

Specification of Letters Patent.

Patented Nov. 22, 1921.

Application filed March 5, 1919. Serial No. 280,889.

To all whom it may concern:

Be it known that HUGH G. HILL, a citizen of the United States, residing at Warwood, Wheeling, in the county of Ohio and State 5 of West Virginia, have invented a new and useful Improvement in Can-Seaming Machines, of which the following is a specification.

This invention relates to machines for 10 seaming can ends to can bodies, and more particularly to machines of this kind in which the movement of the can bodies as they pass through the machine is continuous.

15 The objects of the invention are to provide a machine of this kind of improved and simplified construction in which only one set of seaming rollers or dies is necessary to seam the cans; also to provide a machine of this 20 kind in which the seaming rollers are mounted on a member which moves with a can through a part of its passage through the seaming machine and then returns to its initial position to operate upon the next 25 can; also to arrange two or more seaming rollers on the roller-carrying member, each of the rollers simultaneously performing different parts of the seaming operations on different cans moving through the machine; 30 also to provide mechanism of improved construction for actuating the roller-carrying member; also to provide means of improved construction for rotating the chucks which hold the cans to be seamed; also to improve 35 machines of this kind in other respects hereinafter specified.

In the accompanying drawings:

Figure 1 is a side elevation of a can seaming machine embodying the invention.

40 Fig. 2 is a top plan view thereof.

Fig. 3 is a sectional elevation thereof on line 3—3, Fig. 2.

Fig. 4 is a fragmentary sectional plan view thereof on line 4—4, Fig. 3.

45 Fig. 5 is a fragmentary sectional plan view thereof on line 5—5, Fig. 3, showing the mechanism for moving the seaming devices into and out of operative relation to the cans.

50 The machine is herein described as used for seaming can ends to can bodies, but it is not intended to limit the machine to such use, since the invention may be applied

equally well to machines of other kinds for performing one or more operations on objects other than cans. 55

A represents the base of the machine, which in the construction shown, is mounted on legs a or the like and which is provided with a frame or arch member a' secured to the base and extending upwardly therefrom. These parts may be of any suitable or desired construction.

The means for positioning the cans in the machine, for moving them through the machine, and for holding the same in positions to be seamed may be of any desired construction. In the embodiment of the invention shown in the drawings, B represents the usual rotary feed or positioning device for feeding the cans to be seamed to the seaming machine, and for positioning them in their proper operative relation to the machine. The cans are fed from the feeding device B to a rotary table C provided with a plurality of can-supporting disks or heads c, the upper faces of which in their can-receiving positions are substantially in the same plane as the upper face of the rotary table C, and which have upright stems or pivots c' suitably journaled in bearing members c² arranged in a rotary plate or carrier c³. To facilitate the positioning of the cans on the can-supporting disks c, stops or pockets c⁴ are preferably secured on the table C in operative relation to the can-supporting disks and against which the cans are placed by the positioning device B. Each of the lower can-supporting disks or heads c is arranged below 90 and in operative relation to a corresponding positively driven upper disk or head d. This upper disk or head is secured on a spindle d' also suitably journaled in a bearing d² arranged in a chuck supporting plate or carrier D. Both the lower carrier c³ and the upper carrier D are secured to a central driving shaft E suitably journaled in the base A and the frame a' of the machine, and the table C is rigidly secured on the lower 100 carrier c³ by any suitable means, such as adjustable legs c⁵. The shaft E is provided at its upper end with a bevel gear e which meshes with a gear e' secured on a shaft e². This shaft is driven by means of a gear e³ 105 from a gear e⁴ mounted on the main drive

shaft e^5 of the machine, to which power may be transmitted by any suitable means, such as a pulley e^6 .

Each of the bearing members c^2 is movable vertically to a limited extent relatively to the carrier plate c^3 and is provided at its lower end with a roller f engaging a cam track F suitably secured to the base A of the machine. The cam track F is so formed as to raise the bearings c^2 and the lower can-supporting disks c after the cans have been placed in operative positions on the disks. This clamps the cans between the two disks c and d , comprising the can holding chucks, and the cans are then rotated by contact with the rotating disks d , and at the same time the cans are carried about the axis of the shaft E from the point at which the cans are placed on the machine to a point where the cans are discharged from the machine. The lower can-supporting disks c preferably have a limited lengthwise movement relatively to the bearing members c^2 in addition to being rotatable therein, and are yieldingly held in their upper positions relatively to the bearing members by means of springs f' arranged in the bearing members and pressing upwardly against the plungers f^2 slidably vertically in the bearing members and bearing against the stem c' of the lower can supporting disks. All of these parts may be of any suitable or desired construction and of themselves constitute no part of this invention.

35 The following means are preferably employed to rotate the upper disks d to impart rotary motion to the cans.

Each of the stems or spindles d'' to which the upper disks d are secured is provided at its upper end with a pinion g adapted to mesh with a gear G which is suitably secured to a bevel gear g' rotatably mounted on the shaft E . The gear g' preferably engages the bevel gear e' so that the gear G is rotated in the opposite direction from the shaft E . By means of this arrangement the stems or spindles d'' are rotated at the desired speed, owing to the rotation of the gear G and to the movement of the spindles d'' and the pinions g around the gear G in the reverse direction from the direction of rotation of the gear G . Consequently the gear need only operate at one-half of the speed which would be necessary if the stems d'' were fixed with regard to the frame of the machine.

60 The cans are fed to the machine with the ends in place thereon, and the seaming of the ends to the cans takes place after the cans are secured in the chucks, the following mechanism being preferably employed for seaming the ends of the cans:

65 H represents an arm or member which, in the construction shown, is secured to a sleeve h which is journaled on the shaft

E and rotatable independently thereof. The sleeve and the arm H have an oscillatory movement, during a part of which the arm H travels at the same speed of rotation as the shaft E , and during another part of which the arm H is returned to its initial position. The arm H is provided with seaming rollers I and I' which are adapted to respectively effect the preliminary and final seaming of the cans while the arm H moves at the same speed of rotation as the shaft E . The roller I is mounted on an arm i pivoted at i' on the arm H and the position of the arm i relatively to the cans is controlled by means of an arm i^2 having an anti-friction roller or the like i^3 bearing against a cam i^4 which is suitably secured on the frame of the machine, for example by means of an arm i^5 secured to and extending outwardly from the frame a' . The cam has a face which is proportioned to cause the seaming roller I to move gradually toward the axis of the can during the seaming operation. The arm i to which the seaming roller I for the first seaming operation is secured, is provided with suitable means by which the seaming roller I may be adjusted relatively to the cans. In the construction shown, a pin or screw i^6 is secured to the arm i^2 and extends through a hole in the arm i , the distance between the arms i and i^2 being regulated by means of adjusting nuts i^7 , or the like, which rigidly support the arm i at the desired distance from the arm i^2 and consequently in the desired relation to the cans. The roller I' which performs the final seaming operation on the cans is mounted on an arm i^8 which is connected to an arm i^9 engaging the cam i^4 , by means of a screw i^{10} secured to the arm i^9 and having a nut i^{11} which limits the outward movement of the arm i^8 from the arm i^9 . A resilient or cushioning member i^{12} is preferably inserted between the arms i^8 and i^9 so that the final seaming roller is yieldingly pressed against the can. The seaming rollers I I' are so placed relatively to each other as to act simultaneously on two adjacent cans. The roller I engages the cans after they have been placed on the machine and performs the preliminary seaming operation. As the cans move through the machine, the arm H is returned to a position in which the roller I engages the next can entering the machine and the roller I' at the same time performs the final seaming operation on the can on which the preliminary seaming operation has just been completed by the roller I . One or more seaming rollers or devices may be provided on the arm or member H .

the arm H is mounted. The star wheel receives an oscillatory motion from a star lock member L and a star actuating member L', which are rigidly secured to a shaft l 5 journaled in the rotary plate or carrier c³ and which have a planetary motion about the shaft E. The shaft l is rotated about its own axis by means of a pinion l' secured to the shaft l and meshing with a stationary gear l² secured on the base of the machine. The star lock member has a substantially circular peripheral portion l³ adapted to engage any one of a plurality of similarly curved faces k formed on the star wheel, 10 and while these two faces are in locking engagement, the star wheel and the arm H will rotate at the same speed and in the same direction as the plate or carrier c³ and the cans carried thereby. When these faces move out of locking engagement the actuating arm L' enters one of a plurality of radial recesses or slots k' arranged between adjacent faces k of the star wheel and moves the star wheel and the arm H back to its 15 initial position.

In the operation of the machine, the cans X on being fed to the machine by the positioning device B are clamped between the upper and lower can supporting disks or 20 heads d and e and are carried about the axis of the shaft E. The first seaming roller I then engages the edge of the can top and performs the first seaming operation. When the arm H carrying the seaming rollers is 25 moved in the reverse direction to its initial position by the star actuating device L', the first seaming roller I moves into engagement with a new can which has just been fed to the machine and the second seaming roller 30 I' engages the can on which the first seaming operation has been performed by the roller I. The roller I' completes the operation of seaming the top on the can and is then returned to its starting position to 35 effect the final seaming of the next can. The cans after having been seamed by the roller I' are discharged from the machine by any suitable mechanism, not shown.

The machine described has the advantage 40 of being simple in construction, owing to the fact that only one pair of seaming rollers is necessary to effect the seaming of the cans and that one actuating mechanism serves to control the operation of both seaming rollers. The mechanism described may 45 be used for seaming either of the two ends of the can body, but is particularly desirable for seaming can tops on cans which have been filled since the continuous movement of 50 the cans through the machine avoids spilling of the contents of the cans. Two seaming rollers are shown in the construction illustrated, but the machine could be equipped with one or any desired number of rollers.

65 I claim as my invention:

1. The combination of a rotary carrier for articles to be operated upon, an oscillatory member movable with said carrier, a plurality of devices on said member adapted to operate on said articles to close the same, 70 each of said devices operating on different articles while said member moves with said carrier, one of said devices performing a preliminary closing operation on an article while the other device performs a second 75 closing operation on an article on which the preliminary operation has been performed, and means for moving said member in the reverse direction to move said devices into operative relation to other articles. 80

2. The combination of a rotary carrier for articles to be operated upon, an oscillatory member movable with said carrier, a plurality of devices on said member adapted to operate on said articles to close the same, 85 each of said devices operating on different articles while said member moves with said carrier, one of said devices performing a preliminary closing operation on an article while the other device performs a second 90 closing operation on an article on which the preliminary closing operation has been performed, means for moving said member in the reverse direction to move said devices into operative relation to other articles, and 95 a stationary cam engaged by said devices for moving said devices into operative relation to said articles.

3. In a can seaming machine, the combination of a rotary carrier for moving the 100 cans continuously through the machine, a member movable with said carrier during a part of the movement of said member, preliminary and final seaming devices on said member which are adapted to engage adjacent cans when said member moves with said carrier, and means for moving said member to its initial position to cause said preliminary seaming device to act on another can and to cause said final seaming device to act 105 on the can which has been acted upon by said preliminary seaming device. 110

4. In a can seaming machine, the combination of a carrier for the cans, a seaming device, and means for imparting an oscillatory movement to said seaming device including a star wheel connected with said seaming device, and planetary star lock and actuating members movable with said carrier and actuating said star wheel to give 115 the same an oscillatory movement during a part of which movement said seaming device moves with a can to effect the seaming thereof and during another part of which movement said seaming device moves into 120 operative relation to another can. 125

5. In a can seaming machine, the combination of a carrier for the cans, a seaming device, and means for imparting an oscillatory movement to said seaming device, in- 130

- cluding a star wheel connected with said seaming device, planetary star lock and actuating members pivotally mounted on said carrier and actuating said star wheel to give the same an oscillatory movement, and a fixed gear turning said lock and actuating members about their own pivot, said members giving said star wheel and seaming device an oscillatory movement during a part of which movement said seaming device moves with a can to effect the seaming thereof and during another part of which movement said seaming device moves into operative relation to another can.
5. In a can seaming machine, the combination of a rotary carrier, a seaming device, a star wheel secured to said seaming device pivoted concentrically with said carrier, and a planetary member mounted on said carrier and including a star lock member adapted to engage said star wheel to cause the same to move with said carrier through a part of a revolution and an actuating member for causing said star wheel to be rotated 25 in the reverse direction.
6. In a can seaming machine, the combination of a rotary carrier, a seaming device, a star wheel secured to said seaming device pivoted concentrically with said carrier, and a planetary member mounted on said carrier and including a star lock member adapted to engage said star wheel to cause the same to move with said carrier through a part of a revolution and an actuating member for causing said star wheel to be rotated 25 in the reverse direction.
7. In a can seaming machine, the combination of a rotary carrier, a seaming device, a Geneva movement comprising a star wheel rigidly connected with said seaming device and a star lock and actuating member, and means for giving said star lock and actuating member a planetary motion about said star wheel whereby said star wheel receives an oscillatory movement.
8. In a can seaming machine, the combination of a rotary carrier, a seaming device, a Geneva movement comprising a star wheel rigidly connected with said seaming device and a star lock and actuating member, means 40 for moving said member about said star wheel, and means for rotating said member about its own axis in the same direction as the direction of rotation of said member about the axis of said star wheel, whereby 45 said star wheel receives an oscillatory motion.
9. In a can seaming machine, the combination of a rotary carrier, a seaming device, a Geneva movement comprising a star wheel rigidly connected with said seaming device and a star lock and actuating member, said star wheel being rotatable about the axis of said carrier and said star lock and actuating member being eccentrically and rotatably 55 mounted on said carrier and rotatable therewith, and means for rotating said star lock and actuating member about its own axis to give said star wheel an oscillatory motion.
10. In a can seaming machine, the combination of a rotary carrier, a seaming device, a star wheel secured to said seaming device pivoted concentrically with said carrier, a star lock and actuating member rotatably mounted on said carrier, and a fixed gear 60 for causing said star lock and actuating member to rotate about its own axis, said star lock and actuating member giving said star wheel an oscillatory motion.
11. In a can seaming machine, the combination of a rotary carrier, a seaming device, a star wheel secured to said seaming device pivoted concentrically with said carrier, a planetary member pivoted on said carrier in operative relation to said star wheel, said planetary member including a star lock and a star actuating device, and a fixed gear with which said planetary member engages and which causes the same to rotate about its axis, said lock and actuating member causing said star wheel to move with said carrier during one part of the movement of said star wheel and to cause the star wheel to move to another position relatively to said carrier during another part of the movement of said star wheel.
12. In a can seaming machine, the combination of a rotary can carrier, a seaming device, a Geneva movement including a star wheel secured to said seaming device and rotatable concentrically with said carrier, and a star lock and actuating member mounted on said carrier at a distance from the axis of rotation of the carrier, and means for rotating said star lock and actuating member about its own axis, said star lock and actuating member causing said star wheel to alternately move with said carrier and then to move back to its initial position.
13. In a container closing machine, the combination of a continuously moving carrier for containers, a single set of closing devices each of which is adapted to perform a different part of the closing operation and which operate substantially simultaneously on different containers, means for moving said closing devices into operative relation to different containers while the containers are moving continuously through the machine, and a stationary cam having faces corresponding to each of said closing devices for actuating the same.
14. In a can seaming machine, the combination of a continuously moving carrier for cans, a single set of can seaming rollers each of which is adapted to perform different parts of the seaming operation and which operate substantially simultaneously on different cans, means for moving each roller successively into operative relation to each can while the cans are moving continuously through the machine, arms on which said rollers are mounted, and a stationary cam relatively to which said arms move and which actuates said arms to place the rollers into operative relation to the cans.
15. In a can seaming machine, the combination of a carrier for moving the cans continuously through the machine, a member movable with said carrier during a part of the movement of said member, preliminary

- and final seaming devices on said member which are adapted to engage adjacent cans when said member moves with said carrier, means for moving said member to its initial 5 position to cause said preliminary seaming device to act on another can and to cause said final seaming device to act on the can which has been acted upon by said preliminary seaming device, and a single cam having two faces adapted to actuate said preliminary and final seaming devices to effect the seaming of the cans after the seaming devices have been placed into operative relation to the cans.
- 10 16. In a container closing machine, the combination of a rotary carrier for the containers, an oscillatory member having a movement in one direction with said carrier
- and in another direction to its initial position, and a plurality of closing devices on 20 said member which effect the closing of the container when said member moves with said carrier, and which move into operative relation to other containers when said member moves to its initial position, each of said 25 closing devices performing a different operation on the containers, and a stationary cam which actuates said closing devices to move the same into operative relation to the containers.
- 30 Witness my hand this 27th day of February, 1919.

HUGH G. HILL.
